UNITED STATES PATENT OFFICE.

MICHAEL E. WELSH, OF CHELSEA, MASSACHUSETTS.

CANOPY-TABLE FOR UNDERTAKERS' USE.

SPECIFICATION forming part of Letters Patent No. 400,024, dated March 19, 1889.

Application filed June 21, 1888. Serial No. 277,789. (No model.)

To all whom it may concern:

Be it known that I, MICHAEL E. WELSH, of Chelsea, county of Suffolk, State of Massachusetts, have invented an Improvement in 5 Canopy-Tables for Undertakers' Use, of which the following description, in connection with the accompanying drawings, is a specification, like letters on the drawings representing like parts.

10 This invention has for its object to provide a novel canopy-table for use by undertakers.

The dead are commonly laid out upon tables and subsequently placed in coffins of greater or less cost, and at the present time 15 the most expensive coffins are covered with broadcloth. In accordance with my invention the body is laid upon a table, which may be the usual preparatory table, and is dressed in any desired or usual manner, and to this 20 table is applied, upon suitable legs or standards, a top plate shaped preferably like a coffin-top, and then this top and the table are draped with cloth to resemble a cloth-covered coffin resting on a draped table. At the de- 25 sired time the body may be removed into a coffin of greater or less cost, as may be desired. The top is jointed, so that it may be readily folded for convenience of transportation, and preferably the legs supporting the top are 30 also hinged to be folded into the top.

The invention consists in an undertaker's 35 table simulating a canopied casket, in which the top is made as a coffin or casket top in two parts hinged together, and one part made transparent, and folding legs hinged to said top, and depending draperies attached to said top to form the sides of the casket, as hereinafter particularly set forth and claimed.

Figure 1 in side elevation, partially broken 40 out, represents a canopy-table embodying my invention. Fig. 2 is a similar view with the drapery omitted. Fig. 3 is a detail of the under side of the top, showing the central hinges; and Fig. 4 is a sectional detail showing one of the hinged legs or standards.

The body portion A A' of the table, hinged together at A², has, as shown, folding crossed legs B B', the portion A having a netting or bottom, a, while the portion A' has a bottom portion, a', hinged to a cross-piece, a², so as to 50 be tipped more or less to give to the body the desired position. The table at its four corners receives four legs or standards, c c, each hinged or pivoted, as at c', to the under side of the top plate or cover, C C', preferably 55 made in two parts and hinged together at c², one part, C', being left open for the reception of a glass, at c³, to enable the body to be seen below. The table portion A A' is concealed by drapery D, while suspended from the top 60 plate or canopy is the drapery D', the latter by its fringe covering the upper part of the drapery D, as at the left of Fig. 1.

For convenience of the undertaker, both the top plate and table are jointed centrally, so 65 that they may be folded into compact space and be readily moved from place to place as and when needed.

My improved canopy-table, which with its drapery can be used over and over again, re- 70 sults in economy in funeral expenses.

I claim—

An undertaker's table made to resemble a 75 canopied casket and composed of the hinged and movable top plate, one portion of which is provided with a glass and having legs or supports hinged to said top plate, and draperies adapted to be attached to the top plate to form the sides of the casket, substantially as described.

In testimony whereof I have signed my name 80 to this specification in the presence of two subscribing witnesses.

MICHAEL E. WELSH.
